(57) **CLAIM**

The ornamental design for a finger probe with electrode array, as shown and described.

DESCRIPTION

FIG. 1 is a front, perspective view of a finger probe including an electrode array in accordance with the new design;

FIG. 2 is a rear, perspective view of the finger probe including electrode array;

FIG. 3 is a back view of the finger probe including electrode array;

FIG. 4 is a right side view of the finger probe including electrode array;

FIG. 5 is a front view of the finger probe including electrode array;

FIG. 6 is a left side view of the finger probe including electrode array;

FIG. 7 is a top view of the finger probe including electrode array; and,

FIG. 8 is a bottom view of the finger probe including electrode array.
